(No Model.)

J. J. GRAVES.
HOT WATER HEATER.

No. 423,759.

Patented Mar. 18, 1890.

UNITED STATES PATENT OFFICE.

JOHN J. GRAVES, OF BUFFALO, NEW YORK, ASSIGNOR TO SHERMAN S. JEWETT & COMPANY, OF SAME PLACE.

HOT-WATER HEATER.

SPECIFICATION forming part of Letters Patent No. 423,759, dated March 18, 1890.

Application filed December 23, 1889. Serial No. 334,704. (No model.)

To all whom it may concern:

Be it known that I, JOHN J. GRAVES, a citizen of the United States, residing at Buffalo, in the county of Erie and State of New York, 5 have invented certain new and useful Improvements in Hot-Water Heaters, of which the following is a specification.

My invention relates to hot-water heaters adapted particularly for house-heating purposes; and it consists of a heater of the novel construction to be hereinafter pointed out, and constructed of separable sections which 10 of themselves contain features of novelty.

In the drawings, Figure 1 is a perspective view of a heater embodying my invention, the front casing or shell being removed. Fig. 2 is a longitudinal section of the heater. Fig. 3 is a transverse section thereof. Fig. 4 is a horizontal section on the line $x-x$ of Fig. 3, 20 and Fig. 5 is a horizontal section on the line $y-y$ of Fig. 3.

The boiler or water-heater is made up of a number of hollow sections A, through which the water circulates and is heated. As these 25 sections are duplicates one of another, but one need be described. It consists of two hollow legs 1 and 2, one longer than the other, and connected with each other by a number of pipes 3, thereby leaving the openings 4, which, when the sections are assembled to form a boiler, become the fire-flues for the passage of the products of combustion. The pipes 3 are by preference of the shape in cross-section shown in Fig. 2—that is to say, 30 with the exception of the upper or top one, which is oval, they are flat on their upper and curved on their lower faces. This shape makes the bottoms or floors of the flues 4 flat, so that they may be easily raked or cleaned 40 out, while the other walls thereof are curved, and thus present extended surfaces to the heated products of combustion.

It will be observed that the cross-pipes 3 are of the same width as the water-legs 2 and 45 3, which insures that when the legs are brought together end to end, continuous flues 4 are formed. These sections are arranged opposite to each other in pairs, their shorter vertical legs 2 abutting, and are bolted together

at 5, or otherwise suitably connected. Two 50 or more of these double sections are connected together end to end to form the boiler or heater, the cross-pipes 3 abutting and the openings 4 registering, and the ends of the heater are closed by bonnets or casings, so as 55 to properly direct the products of combustion through the zigzag flue formed by the openings 4 and the casing-walls and plates.

The series of sections A are united by long bolts 6 and 7, passing through lugs or flanges, 60 or preferably, as shown, through the water-tubes 13 and 14, at the lower and upper portions of the sections, respectively, though short bolts uniting adjacent sections might be used. The heater is placed upon a base 65 B of suitable construction, provided with a grate b, so that there is formed a fire-chamber 11 above such grate between the long water-legs 1 and below the lower series of pipes 3 of the sections. The ends of this fire-chamber 70 are closed by fire-brick work 8 inside the casing walls, 9, which close the ends of the heater. The shell or casing walls are formed with or have secured to them the deflecting-plates 10, which extend from the said walls 75 across the ends of the heater and opposite the pipes 3. The preferred arrangement of the deflecting-plates 10 is shown in Fig. 2, where they are shown riveted or bolted to the casing or shell walls 9, and incline thence 80 slightly downward to the opposite ends of the alternate series of pipes 3, against which they may abut, so that there is formed a sinuous or zigzag passage for the products of combustion from the combustion-chamber to the exit-flue 12.

17 is a large door in the casing-wall at the front end of the heater, giving access to the flues to permit their being cleaned.

The water-spaces of the adjacent sections 90 on each side of the central line of the heater communicate at the upper and lower portions of the sections through the water-tubes 13 and 14, so as to maintain a circulation throughout the entire heater. The water is taken in 95 through an opening or port 20 and passed out heated through an outlet-port 21, each one of the sections A being provided with both

an inlet and an outlet port. Such ports as are not used for the pipe-connections of the heater are closed in the usual manner.

Any number of double sections may be connected to form a heater, from three to seven being the usual number for ordinary house-heaters.

A heater made as described is simple in construction and easily set up, and by reason of the very extended flue-surface, which throughout its entire length is surrounded by a water-space, is economical in use. Should any section become worn out or be found otherwise defective, it can be easily replaced at small cost of time, labor, and money, as no particular fitting is required, the sections being duplicates of each other.

Without limiting myself to the precise construction and arrangement of parts shown, what I claim is—

1. A hot-water-heater section consisting of the hollow water-legs of unequal length connected by two or more cross-pipes of a width equal to the width of the water-legs, whereby, when the sections are placed end to end, continuous flues are formed between the cross-pipes, substantially as described.

2. A hot-water heater consisting of a series of hollow water-sections, each having a long and a short leg connected by cross-pipes, the sections being united in pairs, with their shorter legs abutting, and such pairs being

connected end to end with their cross-pipes abutting to form draft-flues through the sections, substantially as described.

3. A hot-water heater consisting of a series of hollow water-sections, each having a long and a short leg connected by cross-pipes, the sections being united in pairs, with their shorter legs abutting, and such pairs connected end to end, a base on which the united sections are placed, and a fire-grate between the longer legs of the section, substantially as described.

4. A hot-water heater consisting of hollow water-sections united end to end and provided with openings through them to form draft-flues in combination with end casing-walls having deflecting-plates arranged adjacent to the opposite ends of the adjacent pipes which separate the draft-passages, substantially as and for the purpose specified.

5. A hot-water heater composed of sections united side by side in pairs and such pairs united end to end, and casings or walls closing the ends of the sections, substantially as described.

In testimony whereof I affix my signature in presence of two witnesses.

JOHN J. GRAVES.
